UNITED STATES PATENT OFFICE.

EDWARD H. THOMPSON, OF CINCINNATI, OHIO.

MECHANICALLY-ACTUATED TOOL.

1,055,572.

Specification of Letters Patent. Patented Mar. 11, 1913.

Application filed January 12, 1912. Serial No. 670,760.

To all whom it may concern:

Be it known that I, EDWARD H. THOMPSON, a citizen of the United States of America, and resident of Cincinnati, county 5 of Hamilton, and State of Ohio, have invented certain new and useful Improvements in Mechanically-Actuated Tools, of which the following is a specification.

This invention relates to mechanically actuated tools and particularly to brushes and similar devices which are adapted to utilize water or other liquids or fluids in performing their functions.

An object of this invention is to produce 15 a new and improved device of the kind above described, which can be more conveniently employed and is more effective in operation, than similar apparatus now in use or known to me. These and other objects I attain by means of a device embodying the features herein described, and illustrated in the drawings accompanying and forming a part of this application.

In the drawings Figure 1 is a longitudinal sectional view along the line 1—1 of Fig. 2 and illustrates a mechanically actuated brush as an embodiment of my invention. Fig. 2 is a transverse sectional view along the line 2—2 of Fig. 1, looking in the 30 direction of the arrow. Fig. 3 is a sectional view along the line 3—3 of Fig. 1 looking in the direction of the arrow.

The illustrated embodiment of my invention consists of a water turbine 4 and a 35 brush 5 which is mounted on, or is directly connected to the shaft 6 of the turbine and is adapted to receive the water discharged from the turbine after it has been employed in imparting motion to the rotor element of 40 the turbine. The turbine illustrated includes a casing 7, which incloses a rotor element 8, and is provided with a liquid supply passage 9, preferably, but not necessarily, formed integrally with the casing and 45 adapted to be employed as a handle for the device. An admission port or nozzle 10 extends through the cylindrical wall of the casing 7 and delivers liquid from the passage 9 to the rotor element 8, which is hereinafter illustrated as a hollow drum provided 50 in its periphery with integrally formed blades 11. The drum is rigidly mounted

on the shaft 6, one end of which is journaled in a suitable step or thrust bearing formed in one end of the casing 7. The 55 other end of the shaft projects through, and is journaled in, an aperture provided in a removable plate 12, which forms the exhaust end of the turbine casing and is provided with a suitably located exhaust port 60 13. The plate 12, is made removable so that the rotor element 8 can be introduced into the turbine and it is adapted to engage an annular shoulder, formed on the casing proper, and to be secured in place by any 65 suitable means, such for example as screws. A longitudinally projecting annular flange 14 is formed on the exhaust end of the casing and, surrounding the plate 12, forms a cylindrical recess at the exhaust end of 70 the turbine, which is concentric with the turbine shaft.

The projecting end of the shaft 6 illustrated, is screw threaded and the brush 5 is mounted thereon by means of a nut 15 which 75 is preferably, but not necessarily, set into the body of the brush so that it forms a part thereof. The shaft is preferably provided with a reverse thread and the nut is correspondingly tapped so that the rotation of 80 the shaft will tend to screw the brush into place on it. It will be understood, however, that any suitable means may be employed for mounting the brush on, or directly connecting it to the shaft 6. The brush may be 85 of any suitable type but it is preferably provided with a circular body, on one side of which the bristles 16 are mounted in any suitable manner and on the other side of which a cylindrical extension 17 is formed. 90 The nut 15 is so located in the extension that the extension is concentric with the shaft 6 and is adapted to project into the cylindrical space surrounded by the flange 14. An annular series of apertures 18 is formed in the 95 body of the brush for the purpose of delivering the water discharged from the exhaust port 13 to the bristles 6 or to the operating face of the brush. These apertures extend from the circular face of the extension to 100 the bristle-mounting face of the brush and are adapted to successively receive the water discharged from the port 13, as the brush rotates with the shaft 6. A series of direct-

ing vanes 20 is mounted on the circular face of the extension and is located between it and the plate 12. Each vane of the series is adapted to direct the flow of water discharged from the port 13 into one of the apertures 18 and also operates to impede the motion, or to decrease the speed of rotation of the brush. This latter function of the vane is not objectionable since, with the 10 type of turbine illustrated, the brush speeds produced by an amount of water, which can be effectively employed in the scrubbing operation of the brush, would be prohibitive, if the water were delivered to the turbine at ordinary water main pressures. For this reason it may sometimes be desirable to so form the vanes that their impeding effect on the brush will be quite marked.

Each vane 20 illustrated extends from a 20 point, on the body of the brush immediately adjacent to the shaft 6, in a substantially radial direction along one edge of one of the apertures 18 to the outer end of the aperture at which point it is curved to conform to the contour of a portion of the edge to the aperture and then projects approximately at a right angle to a radial direction and extends to the peripheral edge of the extension 17 and into close proximity 25 with the inner cylindrical face of the annular flange 14. The outer ends of the vanes extend in a direction opposite to the direction of rotation of the brush and each vane operates to collect a portion of the 30 water discharged from the port 13 and to direct it through its corresponding aperture 18. The tendency of the water discharged from the port 13 is to move outwardly in response to the centrifugal force resulting 35 from the rotary motion imparted to it by the brush. This tendency is, however, overcome by the blades and if desired the blades may be so formed that they will direct the water inwardly toward the shaft 6. The 40 form of the vanes 20 may be varied considerably without departing from my invention.

In the apparatus illustrated I have provided, what may be termed, wearing strips 50 21 between the cylindrical face of the extension 17 and the inner peripheral face of the flange 14. These strips may be formed of soft metal rabbeted into, or otherwise secured to the extension and may be of such 55 altitude that they will engage the inner face of the flange when the brush is first mounted on the shaft. With this arrangement the rotation of the shaft will wear the strips down until they just clear the inner face of 60 the flange so that they will be capable of preventing a flow of water between the flange and the extension without materially impeding the rotation of the brush. Various other forms of packing, however, may be

employed between the extension and the flange if it is found necessary to use a packing.

The passage 9 is preferably several feet long, so that it can be effectively employed as a handle for the device, and it is provided at its outer end with suitable means for connecting it to a hose or any other source of supply.

It will be understood that although I have illustrated a water turbine in connection with my invention that I am not restricted to the type of turbine illustrated, or even to turbine engines since any type of rotary engine may be employed. In addition to this I do not limit myself to water as a motive fluid since air, steam or liquids other than water may be employed. I also wish it to be understood that tools other than brushes may be employed in connection with my invention. For example my invention may be embodied in a floor surfacing machine in which the water discharged from the actuating motor is utilized in the surfacing operation, or it may be employed in any device which includes a rotary tool which utilizes or operates in conjunction with a liquid or a fluid in performing its functions.

I found it desirable to make the operating motor of the device, as light as possible, and for this reason I contemplate making the casing 7 and the rotor element 8 of the turbine of some light metal, such for example as aluminum, and of proportioning the parts so that, while they are sufficiently strong to effectively resist the forces encountered, they do not materially add to the weight of the device.

What I claim is:

1. In a device of the character described, a turbine consisting of a rotor element, a casing inclosing said element and having an inlet port and a laterally disposed exhaust port, a brush mounted on the shaft of the turbine adjacent to the exhaust port, and having transversely extending apertures formed in its body portion which successively pass the exhaust port, and directing vanes mounted on the brush between the brush and the casing, each vane extending radially along one edge of one of the apertures and then at right angles at a point adjacent to the periphery of the brush.

2. A fluid actuated turbine, a tool mounted on the shaft of the turbine and located adjacent to the exhaust port thereof, and directing vanes mounted on the tool and located between the tool and the exhaust port of the turbine for directing the flow of exhaust fluid from the exhaust port to the tool.

3. In combination, a turbine comprising a rotor element, a casing therefor having an

inlet port, an exhaust port and a longitudinally projecting externally located annular flange surrounding the exhaust port, a rotatable element mounted on the shaft of
5 the turbine exterior of the casing and partially surrounded by the flange, and directing vanes mounted on the rotatable element

and located between it and the exhaust port of the turbine.

EDWARD H. THOMPSON.
